DISPENSER FOR HOT CHOCOLATE OR THE LIKE

Richard J. Skiera, 4339 N. Mulligan Ave., Chicago, Ill.,
and Paul K. Phillips, 710 E. Madison St., Lombard, Ill.

Filed Dec. 27, 1960, Ser. No. 63,332

Term of patent 14 years

(Cl. D2—3)

FIG. 1

FIG. 2

FIG. 3

FIG. 2 is a side elevational view thereof taken from the right hand side of FIG. 1.

FIG. 3 is a top plan view thereof with the faucet element omitted for the convenience of illustration.

FIG. 4 is a bottom plan view thereof.

FIG. 5 is a rear view thereof.

The dominant features of the design reside in the portions shown in full lines.

We claim:

The ornamental design for a dispenser for hot chocolate or the like, as shown and described.
